REFLECTOR FOR RECESSED LIGHTING FIXTURES AND THE LIKE

Herman M. Lazerson, Chicago, Ill., assignor to Solar Light Manufacturing Co., Melrose Park, Ill., a corporation of Illinois

Filed Nov. 8, 1963, Ser. No. 77,331

Term of patent 14 years

(Cl. D48—16)

FIGURE 1 is a front elevational view of a reflector for recessed lighting fixtures and the like showing my new design;

FIGURE 2 is a top plan view thereof; and
FIGURE 3 is a bottom plan view thereof.

I claim:

The ornamental design for a reflector for recessed lighting fixtures and the like, substantially as shown.
